FRANK GUY CURTIS, OF MILWAUKEE, WISCONSIN

KNITTED COLLAR FOR VESTS AND COATS

1,105,407.

Specification of Letters Patent. Patented July 28, 1914.

Application filed April 7, 1914. Serial No. 830,165.

To all whom it may concern:

Be it known that I, FRANK G. CURTIS, a citizen of the United States, and a resident of Milwaukee, in the county of Milwaukee and State of Wisconsin, have invented a new and Improved Knitted Collar for Vests and Coats, of which the following is a full, clear, and exact description.

This invention relates to knitted shawl 10 collars of the convertible type for coats and vests, and of such design as to be worn either turned down or standing.

The general objects of the invention are to provide a knitted collar for garments of the 15 character referred to which is knitted in a suitable manner so that the collar will have the proper set when turned down and yet snugly fit around the neck when turned up, the front ends of the collar being provided 20 with a snap fastener so as to closely fit the front of the neck when turned up.

In carrying out the invention the fabric from which the collar is made is knitted in the form of a strip which has alternate zones 25 of tight and loose tension, the actual dimension of the strip between the points of tight tension being such that the strip cut into pieces on these lines of tight tension will produce collar pieces each sufficient to make 30 a collar with the piece doubled along the line of loose tension. The cut edges of the double piece are next trimmed and then sewed to the edge of the neck opening of the garment. By this arrangement the outer 35 edge of the collar is extremely elastic, since it is formed by the zone of loose tension of the strip, and consequently when the collar is turned down it is held in this position by the outer or lower edge of the collar being 40 under tension, whereby it is snugly held against the shoulders. Also, by reason of the elasticity of the outer edge of the collar it can be readily stretched in being converted from a lay-down to a standing collar, or 45 vice versa, and while in a standing position the elasticity or tension will maintain it snugly around the neck. A buttoning device may be employed at the front ends of the collar to close the gap at the throat and 50 at the same time increase the tension throughout the edge of the collar to cause it to more tightly embrace the neck. The ribs of the fabric extend vertically when the collar is upstanding, whereby the ribs contribute to support the collar in this position. 55

For a more detailed understanding of the

invention reference is to be had to the following description and claims taken in connection with the accompanying drawing which illustrates one embodiment of the invention and wherein similar characters of reference indicate corresponding parts in all the views, and in which—

Figure 1 is a front view of a garment with a collar applied thereto and in lay-down 65 position; Fig. 2 is a similar view with the collar in upstanding position; Fig. 3 is a view of a folded, knitted collar piece before the same is trimmed; Fig. 4 is a plan view of a portion of a knitted web or strip from 70 which the collar pieces are cut.

Referring to the drawing, A designates the fabric from which the collars are made, the same being a knitted web or strip which has zones of loose tension alternating with 75 zones of tight tension, the gradation of tension from one zone to the next being uniformly progressive. Thus, in Fig. 4, the zones a, b of tight tension are alternating with the zones c, d of loose tension. As a 80 result, the opposite edges of the knitted web are not parallel but symmetrically sinuous, and the ribs 1 of the fabric are close together in the zones a, b, and more separated in the zones c, d, and consequently the knitted web 85 is transversely elastic to a greater degree along the lines c, d than along the lines a, b. The web is cut into collar pieces 2 by being cut transversely on the lines a, b, and each piece is doubled longitudinally or along the 90 axis of the zone c, d of maximum elasticity, this doubling producing the arcuate form shown in Fig. 3. The corners 3 of the doubled collar piece are trimmed along the dotted curved lines 4, so as to conform more 95 effectively with the edge of the neck opening 5 of the garment B. This trimmed edge of the folded collar piece is fastened to the garment B in any suitable manner, as, for instance, by one or more rows of stitching 6, 100 the points 7 of the collar piece, Fig. 3, forming the front ends of the finished collar, as shown in Figs. 1 and 2. With the collar fastened in this manner the doubled outer edge 8 thereof is formed by the fold on the line 105 through the zone where the tension is of maximum looseness, and consequently when the collar is turned down, as shown in Fig. 1, the outer edge will be stretched, with the resultant effect that the tension will maintain the collar in this position and snugly 110 fit the body of the wearer. The collar when

turned up will naturally remain in standing position, as the ribs of the collar piece extend vertically, and besides the outer marginal portion of the collar is somewhat under tension when in upstanding position; so that the collar will snugly fit the neck. The front ends of the collar may have a buttoning device 9 to close the collar directly at the throat.

10. From the foregoing description taken in connection with the accompanying drawing, the advantages of the construction and method of operation will be readily understood by those skilled in the art to which 15 the invention appertains, and while I have described the device which I now consider to be the best embodiment of the invention, I desire to have it understood that the device shown is merely illustrative and that 20 such changes may be made when desired as are within the scope of the appended claims.

Having thus described my invention, I claim as new and desire to secure by Letters Patent:

25. 1. A garment having a collar capable of assuming an upstanding or turn-down position, said collar being made of a knitted strip having a longitudinal zone of loose tension forming the outer edge of the collar

and a zone of tight tension along the portion fastened to the garment. 30

2. A garment having a collar capable of assuming an upstanding or lay-down position, said collar being made of a knitted piece doubled longitudinally and having a 35 medial zone of loose tension and marginal zones of tight tension, the zone of loose tension forming the outer edge of the collar and the zones of tight tension forming the inner edge that is fastened to the garment. 40

3. A garment having a collar capable of assuming an upstanding or lay-down position and made of a knitted piece folded longitudinally, the line of fold forming the outer edge of the collar and the edges being 45 fastened to the garment, the ribs of the collar extending transversely to the folded and attached edges of the collar, and the tension of zones transverse to the ribs progressively decreasing from the attached edge to the 50 outer edge thereof.

In testimony whereof I have signed my name to this specification in the presence of two subscribing witnesses.

FRANK GUY CURTIS.
